ELECTRICAL DUST PRECIPITATOR

Peter H. Wyckoff, Avalon, Pa., assignor to Westinghouse Electric & Manufacturing Company, East Pittsburgh, Pa., a corporation of Pennsylvania

Application February 29, 1940, Serial No. 321,464

4 Claims. (Cl. 183—7)

My invention relates generally to electrical precipitators for removing dust from flowing gases, the dust being suspended or contained in the gases, and more particularly relates to the type of precipitator which is provided with an ionizing zone for electrically charging the gas-borne dust, and a separate precipitating zone for subsequently precipitating the charged dust.

It is a broad object of my invention to provide an electrode for an electrical precipitator, which is substantially self-cleaning.

It is another object of my invention to provide an electrode for a precipitator employed for cleaning gases having high dust concentrations, such as are encountered in some industries. An example of such an application may be found in boiler rooms, especially the more recently-designed stations employing powdered coal as a fuel. With modern methods and devices for rapid burning, the flue gases may contain as much as 1.4 grains of dust per cubic foot, and even more, and in larger installations the flue gases may carry as much as 2 tons of dust, or more, per hour, the dust being a fine powdery ash comprising particles ranging in size from a fraction of a micron to about 200 to 300 microns, and varying in electricity-conducting properties from highly-conductive carbon particles to practically insulating solid oxides or other forms of ash.

The usual precipitator of the multi-zone or multi-stage type comprises at least two zones through which the dust-laden gases flow, in the first of which the dust is charged or ionized, and in the second of which the charged dust is precipitated. However, in the general form of precipitators of this type there may be some deposit of dust particles on the elements of the first ionizing zone which either collect on these elements, or, if they be conducting, lose their charge after contacting the elements, and then flow uncharged through the precipitating zone and, consequently, are not deposited or collected but flow out with the treated gases. In either case, the result is a lowering of the overall efficiency of the unit. Where a large volume of dust must be continuously removed, these disadvantages are considerably aggravated and require the deenergization of the elements so that they may be cleaned by jarring or by some other means. Moreover, during such cleaning it may be necessary to divert the gas flow so that smaller particles or agglomerated particles which burst from the falling dirt, will not be blown out of the precipitator.

My invention is particularly directed to pro-

viding a form of electrode for the ionizing zone of a multi-stage precipitator which will be substantially self-cleaning so that it will be continuously efficient and relatively clean during continued use.

It is a further object of my invention to provide a multi-stage electrical precipitator for cleaning gases having high dust concentrations in which the dust contains a good proportion of carbon particles or other particles having fairly good electricity-conducting properties, that is, particles of relatively-low resistivity or relatively-high conductivity.

It is a further object of my invention to provide an electrical precipitator for cleaning gases in which the amount of dust to be removed may rise to considerable proportions; a more particular object being to provide an electrode in the ionizing zone of such a precipitator, which electrode will remain efficient with continued use, and will automatically discharge any dust deposited thereon into a convenient receptacle.

The ionizing zone, for the type of precipitator to which my invention especially relates, comprises electrodes defining an ionized electrostatic field, with one side or end of the field being relatively highly concentrated and the other, relatively distributed. The electrode, or electrodes, at which the field is concentrated are the means for creating the ions which flow toward the other electrode, or electrodes, which bound the less concentrated field. In practice, the former may assume the shape of a wire or other equivalent elements having a relatively-small cross-sectional area, as compared to the latter, which are spaced from the wire, and which have a relatively-large surface area. These characteristics and functions may conveniently serve to identify the various electrodes. For example, the smaller electrodes may be designated as the high-gradient electrodes, while the others may be called the low-gradient electrodes. Or, if the basis for identification be the functions of the electrodes, then the smaller electrodes may be called the ionizing-wires or ionizing-electrodes while the larger electrodes can be called the collector-electrodes, or receiving-electrodes. Other common terms for the respective electrodes, which are frequently employed in the prior art, are "ionizing-wire" for the smaller electrode, and "ground electrode" for the larger. In the specific embodiments to be described, I prefer to employ the terms "ionizing-electrode" for the smaller electrode, and "receiving-electrode" for the larger electrode, modi-

fied, perhaps, by adjectives descriptive of the physical attributes of the diverse electrodes.

Other objects and features of my invention will be gathered from the following description thereof, which is to be taken in conjunction with the accompanying drawings, in which:

Figure 1 is a horizontal sectional view, symbolically drawn, of a precipitator built in accordance with my invention.

Fig. 2 is a perspective view of one of the receiving electrodes of Fig. 1.

Fig. 3 is a fragmentary perspective view showing a modified form of an ionizing electrode.

Fig. 4 is a fragmentary sectional view of a further modification of an electrode adapted to be used in an ionizing zone comprising more than one ionizer unit; and,

Fig. 5 is a graph of cleaning efficiency against gas velocity for a precipitator employing, planar electrodes in the ionizing zone, and for a precipitator employing electrodes in accordance with my invention.

A precipitator built along the lines of my invention comprises an ionizing zone 2 and a precipitating zone 4 successively in the direction of the gas-flow which is indicated by the arrows in Fig. 1.

The ionizing zone comprises one or more ionizer units, each of which includes an ionizing-electrode 6, which in this instance is shown in the form of a round wire, and two receiving-electrodes 8 disposed on each side of the ionizing-electrode 6, and relatively insulated therefrom so that the terminals of a source of energy may be, in effect, connected, on the one hand, to the ionizing-electrode, and on the other hand to the electrodes 8, thereby creating an electrostatic field between the ionizing-electrode and the receiving-electrodes. Preferably, for precipitators for industrial application a unidirectional source of power is employed with the ionizing-electrode 6 maintained negative and the receiving-electrodes positive.

A receiving-electrode in accordance with my invention may take any one of a number of forms but the specific form herein described comprises a hollow, flat, channel or box-like structure open at the bottom and at the side which faces the ionizing-electrode. As shown in Fig. 2, the receiving-electrode 8 comprises a rear side 10 relatively elongated in the direction of gas-flow, as compared to sides 12 transverse to the direction of gas-flow. The front side comprises a plurality of spaced wires 14 secured to flanges or edges 16 along the top and bottom of the front side of the electrode. In one specific embodiment I employ No. 10 wire having a length which will be, of course, dependent upon the capacity of the unit. The wires are spaced $\frac{3}{8}$ " apart between centers, the end wires being spaced $\frac{1}{2}$ " from side edges 18 of the front side, which parallel the wires. The ionizing-electrode 6 may be of any suitable size, and a wire of approximately 30 mils has been found satisfactory.

I have found that with a distance of approximately 2" from the plane of the wires to the center of the wire 6, with a unidirectional voltage of approximately 26 kilovolts between the wire 6 and electrodes 8, and an ionizing current of about 350 microamperes per foot of ionizing wire, a depth of $\frac{1}{2}$ " to 1" between the front and rear sides of the electrode 8 yielded satisfactory results.

The precipitating non-ionizing zone of the unit

comprises a plurality of non-discharging relatively-insulated precipitator-plates 20 and 24, alternately spaced, and having a unidirectional voltage between them yielding a unidirectional gradient of approximately 13,000 volts per inch of spacing, with the series of plates 20 at one polarity and the series of plates 24 at the other polarity, as is customary.

In order to determine the relationship of my receiving-electrodes in a precipitator of this kind compared to continuous, planar receiving-electrodes of the same dimensions, I carried out a series of tests with both types of electrodes, the results being shown in Fig. 5. In this figure the efficiency of the units were determined in accordance with the so-called "blackness test" evolved by the United States Bureau of Standards, and the solid line represents the efficiency of a unit constructed with the planar electrodes, that is, electrodes in which the front side was made a solid metal rather than spaced wires as shown in Fig. 2. The short-dash line indicates the drop in efficiency of such a unit as the solid electrodes coat over with a layer of dirt and, as may be expected, the efficiency drops at commercially-useable gas velocities. However, the long-dash line shows the efficiency of the unit with open-mesh grid-type receiving-electrodes built in accordance with my invention, with the same total amount of gas and dust passing through the unit as was the case in determining the short-dash line curve. The dust used in obtaining these curves was fly ash such as passes with flue gases resulting from the burning of powdered coal. It is at once apparent that with the use of my electrode the efficiency of the unit is considerably increased, especially at the higher rates of gas velocity. Thus, for an efficiency of about 85%, a unit with receiving-electrodes having a continuous metallic surface can be operated with a gas-flow of about 400 feet per minute, whereas the same unit with my electrodes can handle, with the same efficiency, a gas-flow of above 500 feet per minute.

Investigating the causes of the difference in efficiency between a precipitator employing the grid-type electrodes and one employing planar electrodes in the ionizing zone, I have discovered that one of the primary reasons for the difference is due to the fact that the dust contained a good percentage of conducting particles, in this case carbon. From observation of the action of a precipitator with continuous-surface receiving-electrodes, and from chemical analyses determining the carbon content of the gases before entering the precipitator, and the dust deposited on the various electrodes, I explain the operation of such precipitators in the following manner.

The carbon particles are quickly charged in the ionizing zone and are attracted to the large electrodes of this zone before they can pass out of it. They will adhere to these electrodes if some adhering factor is present, or, if not, will ultimately pass into the precipitating zone, perhaps with their charges neutralized. If neutralized, the particles rapidly flow through the precipitating zone with the gases, and if not neutralized, they merely rebound or bounce over the surface of the precipitator-plates, and finally also flow along with the gases out of the precipitating zone.

If dust particles adhere to the electrodes, the ionizing efficiency is soon decreased. If they flow out of the unit with the gases, the gases are not

thoroughly cleaned. In either case, a decrease in cleaning efficiency results.

However, a unit with trough-shaped receiving-electrodes of metal covered with a grid on the side facing the ionizing-electrode, operates in a considerably different manner. In this case, when the conducting particles are attracted to the grid electrode, they pass through the spaces between the wires and are discharged against the back of the trough which acts as a confining pocket for the particles, the particles falling down into a small hopper or receptacle which may be arranged below the open bottom of the electrode. I explain this action by the difference in the intensity of the field in front of the grid as compared to the intensity of the field between the grid and the rear side of the electrode, the former being relatively intense so that the dust particles will be charged, and the latter being relatively weak since it has metal at the same polarity along all its sides. The spaces between the wires permit some of the lines of force from the ionizing-electrode to extend to the rear side of the trough and this factor appears to be important in the design of a receiving-electrode in accordance with my invention, since the spacing should be such that the field within the electrode will be insufficient to recharge the carbon particles by induction, or otherwise, after they contact the rear side, so that they will fall down of their own weight into a receiving receptacle below.

A large percentage of the ionizing current is taken by the grid wires, and only a small percentage is permitted to leak through the grid wires to the back wall of the electrode. Thus when a carbon particle is charged in the ionizing zone, it is attracted towards the grid-type receiving-electrode in the same manner as in the case of a solid receiving-electrode. When the particle reaches the grid-type electrode, it passes through the grid wires, is substantially neutralized, and finds itself in a region of very weak field, and falls by gravity down the inside chute into a convenient receptacle. As it is falling down the chute, any tendency to wander out through the grid will be repulsed by the electrostatic field and by bombardment by other particles entering the grid structure. Accordingly, any particles which tend to precipitate prematurely on the receiving-electrode will be removed as quickly as they are precipitated. It is highly probable that some very fine particles actually agglomerate on the back side until they attain a size sufficient to permit them to fall.

Should a conducting particle strike a grid wire, it would bounce off after losing its charge but would be struck by the stream of ions flowing from the ionizing-electrode, or other charged dust particles, and consequently enter the next vacant space and thus be trapped. High-resistance particles which strike a grid wire will tend to build up a film over the wire, which builds up to a definite thickness. When this thickness reaches equilibrium, any further high-resistance dust which is deposited merely rolls over the surface of the dust pile and is drawn into the adjacent space. Since the particles are of high resistance, they will retain part of their initial charge, and will be drawn towards the back of the trough due to the small gradient existing within the receiving-electrode itself. Particles of high conductivity, on the other hand, may actually jump away from a grid wire, after contact therewith, and are ultimately reprecipi-

tated again, inside the electrode, by contact with the ion stream.

I have found that the grid wires of my electrode did coat with a thin layer of dust but that this layer would automatically peel off in small sections, or chunks, which were sufficiently large to drop by their own weight against the forces of the electrostatic field and gas-flow. Any fine spray accompanying a falling chunk of dust would agglomerate, or be recharged sufficiently to enter one of the succeeding spaces of the grid and pass into the hollow of the electrode where it would be discharged and fall as described before.

I am fairly convinced that a precipitator in accordance with my invention collects, in the ionizing zone, practically all of the carbon content of the fly ash. With fly ash containing 17% carbon, a precipitator without my electrode showed only 9% carbon in the dust collected, whereas with a grid type electrode the deposit gathered from the hopper beneath the receiving-electrodes showed a carbon content of 40%, and further indicated that practically all of the carbon in the gas had been precipitated.

I further found that the thickness of the built-up dirt on the grid-type receiving-electrode was only about $\frac{1}{8}$ " before it began to break or chunk off, whereas with a continuous, planar, receiving-electrode of metal the dirt would build-up to a thickness of $\frac{1}{2}$ ", or more, before breaking off in chunks. Moreover, the latter dirt stuck quite tenaciously, probably due to the constant ionic bombardment from the ionizing-electrode.

The use of a grid-type receiving-electrode has, consequently, certain pronounced advantages such as those described. Additionally, other practical advantages are present. For example, with only a $\frac{1}{8}$ " thickness of dirt building-up on each of the grids as compared to $\frac{1}{2}$ " or more on a flat plate, a number of deleterious effects are avoided depending on the conductivity of the particles. Thus, if the dust deposited is highly conducting, it would decrease the spacing or clearance between the ionizing and receiving electrodes, and consequently excessive arcing may occur which would momentarily drop the voltage due to the heavy drain on the power supply, or would jar collected dirt from the precipitating elements into the gas stream. If the dirt is of a medium resistivity, the effect of a thicker layer of dirt would be the same as a series resistor due to the high voltage drop across the dirt layer, and it is common to observe a 50% drop in ionizing current as a flat field electrode coats over. With a layer of dirt of high resistivity, a thinner film coating, such as obtained with my invention, decreases the effect of back ionization, so that the tendency to introduce ions of opposite sign from those desired for dust-charging, and consequently neutralization of charged particles is considerably decreased. Accordingly, by substituting an electrode in accordance with my invention in a multi-zone precipitator, I improve its performance in a number of respects.

In Fig. 3 I show a modified form of receiving-electrode in which the spaced wires are replaced by expanded metal which is secured, as by welding, to the edges of the front side of the electrode. I have found that, with conditions as previously described, expanded metal .094" thick with a diamond shaped mesh of $1\frac{5}{16}$ " x 2" would operate satisfactorily with air velocities up to 500 feet per minute and even greater. Smaller meshes tend to clog up and render the unit less effective.

In Fig. 4 I show a further form of modified unit for use in an ionizing zone comprising more than one aligned ionizer unit, each unit comprising two ionizing-electrodes and three cooperating receiving-electrodes. The central electrode of this unit is made relatively deep, and has a central partition 30 dividing it into the equivalent of two separate receiving-electrodes, one facing toward an ionizing-electrode 32 disposed at one side of the combined unit, and the other facing another ionizing-electrode 34 on the other side.

While I have described my invention in the form in which I now believe to be the best mode of application thereof, it is obvious that many equivalent forms can be conceived.

I claim as my invention:

1. An electrical precipitator for cleaning a flowing particle-laden gas, comprising a first zone; a second zone closely spaced from the first zone in the direction of gas-flow; ionizing-electrode-means substantially centrally disposed in said first zone, and extending transversely with respect to the gas-flow, for charging substantially all of the particles carried by the gas; precipitating-electrode-means disposed in said first zone in laterally spaced relation to said ionizing-electrode-means, considered with reference to the direction of gas-flow, said precipitating-electrode-means comprising means whereby charged particles of certain types including substantially all of the particles of relatively higher conductivity are selectively precipitated and continually removed from the boundary of the gas-stream in said first zone; the particle-charging effect of the ionizing-electrode means being sufficiently strong, the extent of the precipitating-electrode-means in the direction of gas-flow being sufficiently limited, and the velocity of the gas-flow being sufficiently high, so that other charged particles remain in charged condition in the gas as it leaves the first zone and enters the second zone; and a plurality of relatively closely spaced precipitating-electrode-means of alternately opposite potentials substantially filling said second zone for removing said remaining particles with a much smaller mean transverse-flow path than in the case of the particles precipitated in said first zone.

2. The method of removing particles from gases laden with particles of various degrees of electrical conductivity, including particles of relatively higher conductivity, which method comprises passing the gases through an ionizing electrostatic zone in the gas-flow path for charging substantially all of the particles and causing a predominating part of the charged particles of

relatively higher conductivity to be precipitated in a pocketed area in said ionizing electrostatic zone, whereby these particles of relatively higher conductivity are removed from the gas-flow path, and then passing the gases through a non-ionizing electrostatic zone in the gas-flow path for causing charged particles remaining in the gases, leaving the ionizing electrostatic zone, to be precipitated in said non-ionizing electrostatic zone.

3. The method of cleaning flowing flue gases containing gas-borne particles comprising a relatively small percentage of conductive carbon particles and a larger percentage of ash particles, which comprises simultaneous electrical charging of substantially all of the particles and electrically precipitating substantially all of the charged carbon particles in a pocketed area in an ionizing zone in the path of the flowing gases, while permitting charged ash particles to pass beyond the ionizing zone, and then electrically precipitating substantially all of the charged ash particles remaining in the gases in a non-ionizing electrostatic zone which is next to and follows the said ionizing zone in the path of the flowing gases.

4. A gas-cleaning electrical precipitator device for cleaning a flowing gas, such as flue gas, containing particles of varying degrees of resistivity, such as carbon and ash, said precipitator device having an ionizing zone and a precipitating zone successively in the direction of gas-flow, said ionizing zone having ionizing-electrode means and spaced receiving-electrode means cooperating with said ionizing-electrode means for establishing an ionized electrostatic field for charging the dust particles in the gas flowing through said field, said receiving-electrode means being of limited extent in the direction of gas flow and including chamber means providing a collecting pocket having a grid-front presented to said ionizing-electrode means for causing charged dust particles of relatively higher conductivity, such as carbon, to migrate into said collecting pocket and be collected in said chamber means while permitting charged dust particles of relatively lower conductivity to flow with the gas beyond said chamber means, said precipitating zone comprising precipitating means for separating pre-charged dust particles of relatively higher resistivity, such as ash, from the gas, said precipitating means comprising a plurality of alternately relatively insulated and non-insulated precipitator-plate-electrodes of limited extent in the direction of gas-flow, upon which the last said dust particles precipitate.

PETER H. WYCKOFF.
